UNITED STATES PATENT OFFICE.

ENOCHE OENSTRAND, OF SYRACUSE, NEW YORK, ASSESSOR TO U. S. STEEL FURNITURE COMPANY, OF SYRACUSE, NEW YORK, A CORPORATION OF NEW YORK.

FURNITURE.

1,153,947.

Specification of Letters Patent. Patented Sept. 21, 1915.

Application filed May 7, 1913. Serial No. 763,052.

To all whom it may concern:

Be it known that I, ENOCHE OENSTRAND, of Syracuse, in the county of Onondaga and State of New York, have invented a new and useful Improvement in Furniture, which improvement is fully set forth in the following specification and shown in the accompanying drawings.

The present invention relates to furniture and more particularly to that type which is constructed from sheet metal, an object of this invention being to provide an improved wall construction and an improved drawer suspension.

15 To these and other ends the invention consists in certain parts and combination of parts all of which will be hereinafter described, the novel features being pointed out in the appended claims.

20 In the drawings: Figure 1 is a front view of a sheet metal desk embodying the present improvements; Fig. 2 is a horizontal section through the desk; Fig. 3 is a detail view showing the manner of supporting the rear ends of the drawer guides; Fig. 4 is an enlarged vertical section on the line *a—a*, Fig. 1 with the drawer removed; Fig. 5 is an enlarged section on the line *b—b*, Fig. 4; Fig. 6 is a section on the line *c—c*, Fig. 4; Fig. 7 is a section on the line *d—d*, Fig. 4; Fig. 8 is a detail perspective view showing portions of one of the legs of the desk and portions of the strike bars connected thereto; and Fig. 9 is a detail view of the forward end of one of the drawer guides. Fig. 10 is a detail of a side panel connection with one of the legs.

25 In the embodiment of the invention herein illustrated, the desk comprises a drawer section which does not form any part of the present invention and will therefore be described only generally. Four hollow legs 1, 2, 3 and 4 are connected together at the rear of a section by a panel 5 and at the sides by panels 6 and 7. The front legs 1 and 2 are connected by strike bars 8 between which operate the drawers 9 and a slide 10. Also embodied in the desk is a wall which forms part of the present invention and which comprises two hollow sheet-metal legs 11 and 12, one at the front of the desk and the other at the rear of the desk, said legs being connected together by two sheet metal panels 13 and 14 preferably arranged in spaced and parallel relation. In

order that these panels may be connected to the legs, the latter have their opposed faces slotted preferably from their upper ends to a point on the lever to the lowermost strike bar 8. The two panel plates project into these slots and are provided at their vertical edges with flanges 17 which abut the inner walls of the leg at 18 and also abut the free edges of the flanges 15 which are turned inwardly from the legs on opposite sides of the slots, the said flanges 15 bearing against flat faces of the sheet metal panels. Any suitable means may be employed for holding the panels in these positions but it is preferred to provide the flanges 15 with openings 16 which receive tongues 19 struck up from the panels, the panels being fitted to the legs first by introducing the tongues into the openings 16 and then moving the panels downwardly in their planes to effect an interlocking connection between them and the legs. The wall thus formed is connected to the drawer section in spaced relation to the latter to provide a foot space for the user of the desk. A top 20 of any suitable construction unites the two parts in this instance. Operating between the drawer section and the wall just described is a drawer 21 for which there has been provided a novel drawer suspension 25 forming one of the features of this invention. This drawer suspension embodies two strike bars or pieces, one arranged above the other and connecting the wall with the drawer section. The lowermost bar is 30 formed from a sheet of metal bent to form an upper horizontal portion 32, a vertical portion 33 depending from the forward edge of the horizontal portion 32 and a horizontal lower portion 34 extending rearwardly from the lower edge of the vertical portion 33 and having an upwardly-turned flange or portion 35 in rear of the upper horizontal portion 32. Each of the horizontal portions 32 and 34 are provided with 35 perforated lugs 36 at opposite ends passed through slots in the adjacent legs 1 and 11 and provided with perforations.

The upper strike bar has two horizontal portions 37 connected at their fronts by a vertical portion 38, the lower horizontal portion 37 having an upward extension 39. This strike bar, like the lowermost strike bar has, at each end, a pair of perforated lugs 36 passed through slots in the legs and 40

pins or rods 40 pass through these perforated lugs and the lugs on the lowermost strike bar to hold these parts to the legs and also tie the double wall to the drawer section.

In addition to the strike bars each drawer suspension embodies two guide members each formed from a sheet metal strip. Each strip preferably comprises a main or body portion 22 vertically arranged and having near its lower edge a lateral guide 23 for cooperating with the side of a drawer as will be seen by referring to Fig. 5, such lateral guide being formed by bending the strip inwardly from the main portion 22 as at 24 and thence downwardly. The forward end of this guide 23 flares or is beveled outwardly at 25 to facilitate the introduction of a drawer and to close the opening which would otherwise be formed, this beveled portion being a lip on the sheet metal strip in alignment with the guide 23 when the strip is cut and afterward bent or deflected to the position shown in the drawings. Each drawer guide member is also provided with a bottom guide 26 which is preferably formed by bending a portion of the sheet metal strip, beyond the lateral guide 23, inwardly at right angles to the said guide 23. Beyond the bottom guide 26, the sheet metal strip is bent downwardly at 27 and outwardly at 28 parallel with the bottom guide 26 but extending beyond the latter to a point in alignment with the outer face of the bottom portion 22. The portions 27 and 28 are provided for the purpose of giving strength to the bottom guide 26 and of providing means for suitably sustaining the guide as a whole within the furniture. At the upper part of the body portion 22 a top guide 29 is provided formed by bending the metal strip inwardly and thence upwardly at 30 to strengthen the top guide. The front end of this top guide 29 and its strengthening rib 30 do not extend so far forward as does the body portion 22 and this is also true of the bottom guide 26 and the parts 27 and 28, although the bottom guide 26 does project at 31 beyond the parts 27 and 28 and all of these parts project forwardly beyond the parts 29 and 30. To support the front ends of the guides each of the latter interlocks with one of the front supports or legs 1 and 11. For this purpose, such legs are provided with openings 41 between the two strike bars to receive a tongue 42 struck up from the guide and preferably from the forward end of the body portion 22, said tongue being passed through the opening 41 to cooperate with the inner face of the legs as shown in Figs. 6 and 7. When in this position, those portions of the guide member between the upper edge of the body portion 22 and the bottom guide 26 lie between the two strike bars. The guide face of each top

guide 29 alines with and is in a horizontal plane with the under surface of the lower portion 37 of the top strike bar and the forward end of the top guide 29 and the strengthening rib 30 abut the upward extension 39 of the top strike bar. The projecting portion 31 of the bottom guide rests on the upper portion 32 of the lower strike bar, while the outwardly-turned portion 28 of the guide member rests upon the top face of the lower portion 34 of the lower strike bar, its outer edge abutting the proximate leg as shown in Fig. 5. The upwardly-turned flange 35 of the lower strike bar is cut away at 43, Fig. 8, in order that the part 28 may coöperate with the part 34 and the ends of this flange form shoulders which coöperate with the guide member to prevent lateral movement of the lower parts of said members. The supporting means for the rear ends of the guides embodies, in this instance, portions 44 turned outwardly from the rear ends of the guide members and extended rearwardly at 45 to lie in contact with the proximate panel of the desk, rivets 46 securing them in place. The rivets may also be employed for securing a connecting piece 47 which abuts the outwardly-turned portions 44 of the guide members and has rearwardly-turned portions 48 held by the rivets 46.

The drawer 21 which may be of any suitable construction is preferably made of sheet metal with heads 49 along the upper edges of its side walls to coöperate with the top guide 29 and the body 22 as shown in Fig. 5.

According to the present invention, there is provided a sheet metal wall of strong and durable construction which can be made to simulate a wooden construction in form and thickness. There is also provided a drawer suspension which may be readily assembled and which is composed of a minimum number of parts joined together in such a manner as to produce a rigid structure. Furthermore, the drawer is so guided as to prevent any binding or jamming of the parts.

What I claim as my invention and desire to secure by Letters Patent is:

1. A drawer suspension comprising suitable supporting means, a pair of guide members each formed from a single piece of sheet metal having a vertically arranged body portion, a portion extending inwardly from the body portion to coöperate with the bottom of the drawer, a portion extending downwardly from the last-named portion, and a portion extending outwardly from the downwardly-extending portion to a point in a plane with the outer face of the body portion.

2. A drawer suspension comprising a suitable supporting means, a pair of guide members each formed from a single piece of sheet

metal having a vertically arranged body portion, a portion turned inwardly from the upper part of the body portion to coöperate with the top of a drawer, a portion turned inwardly at the lower part of the body portion, a portion turned downwardly from the inwardly-turned portion to provide a lateral guide for the drawer and a portion turned inwardly from the lower part of the lateral guide portion to coöperate with the bottom of the drawer.

3. A drawer suspension comprising a suitable supporting means, a pair of guide members each formed of a single piece of sheet metal having a vertically arranged body portion, a portion extending inwardly from the lower part of the body portion, a portion turned downwardly from the inwardly-turned portion to provide a lateral guide for the drawer, a portion turned inwardly from the lower part of the lateral guide portion to coöperate with the bottom of the drawer, a lip being formed on the sheet metal strip in alignment with the lateral guide portion and being deflected outwardly to provide an inclined portion, facilitating the introduction of the drawer.

4. In a drawer suspension, the combination with a pair of drawer supports of a strike bar arranged between them, said strike bar having an upper portion forming the bottom of the drawer opening and a lower portion connected at its forward part to the forward part of the upper portion and extending in rear of the upper portion, being provided with an upwardly-turned flange which is spaced at its ends from the front supports to form a shoulder, and a pair of guide members each secured to one of the front supports and above the strike bar, having an inwardly-extending portion for coöperation with the bottom of the drawer, said inwardly extending portion being substantially in a plane with the top of the strike bar, and said guide member also having a portion extending downwardly therefrom to coöperate with one of the shoulders at an end of the flange on the lower portion of the strike bar.

5. In a drawer suspension, the combination with a pair of front supports, of a strike bar connecting the supports and having shoulders in proximity thereto, and guide members each interlocking with one of the supports, and having a portion aligned with the top face of the strike bar and a portion engaging the shoulder to prevent inward movement of the lower part of the guide member.

6. In a drawer suspension, a pair of front supports forming the side walls of the drawer opening, a strike piece forming the

bottom wall of the drawer opening and having notches in proximity to the front support, and a pair of guide members interlocking with the front supports and engaging within the notches of the strike piece to be held against lateral movement.

7. In a drawer suspension, the combination with a pair of front supports, and a strike piece connecting them, the supports being provided with openings above the strike piece and the strike piece being provided with shoulders in proximity to the supports, of guide members having tongues projecting through the openings to engage the inner faces of the supports, said guide members engaging behind the shoulders and held against inward movement by the latter.

8. In a drawer suspension, the combination with a pair of front supports, and upper and lower strike bars connecting them, of guide members formed from sheet material and each having vertical body portions interlocking with a front support between the upper and lower strike bars, an inwardly-turned portion at the upper part of the body portion formed with an upwardly-turned flange lying behind the uppermost strike bar, an inwardly-turned portion coöperating with the bottom of the drawer and lying substantially in a plane with the upper face of the lowermost strike bar.

9. The combination with a pair of front supports, of an upper and a lower strike bar connecting them, the lower strike bar having upper and lower portions connected at their front edges, the lower portion of the lower strike bar projecting in the rear of the upper portion and having an upwardly-turned flange at its outer edge, said flange being spaced from the front supports, guide members each formed from sheet material and comprising a body portion secured to a front support between the strike bars and having, at the upper part thereof, an inwardly-turned portion to coöperate with the top of the drawer and, at the lower part thereof, an inwardly-turned portion to coöperate with the bottom of the drawer, the forward end of said inwardly-turned portion resting upon the top portion of the lower strike bar, there being provided also on each guide member a portion depending from the bottom guide and bent outwardly to coöperate with an end of the flange on the strike bar and also with the upper surface of the lowermost portion of the lower strike bar.

ENOCH OHNSTRAND.
